United States Patent Office

Des. 209,974

Patented Jan. 23, 1968

209,974

CLOCK RADIO OR SIMILAR ARTICLE

Victor Reichenstein, Great Neck, N.Y., assignor to Consolidated Merchandising Corp., New York, N.Y., a corporation of New York

Filed July 11, 1966, Ser. No. 3,018

Term of patent 7 years

(Cl. D42—7)

Fig. 1

Fig. 2

Fig. 3

Fig. 4

Fig. 5

Fig. 6

FIG. 1 is a front perspective view of a clock radio or similar article showing my new design;

FIG. 2 is a front elevational view thereof;

FIG. 3 is a side elevational view thereof;

FIG. 4 is a top plan view thereof;

FIG. 5 is a rear elevational view thereof; and

FIG. 6 is a bottom plan view.

I claim:

The ornamental design for a clock radio or similar article, substantially as shown.
